UNITED STATES PATENT OFFICE.

WILLIAM TOWLER, OF LAWRENCE, MASSACHUSETTS.

WEFT-REPLENISHING LOOM.

1,363,544.

Specification of Letters Patent. Patented Dec. 28, 1920.

Application filed March 28, 1918. Serial No. 225,358.

To all whom it may concern:

Be it known that I, WILLIAM TOWLER, of Lawrence, in the county of Essex and State of Massachusetts, have invented certain new and useful Improvements in Weft-Replenishing Looms, of which the following is a specification.

This invention relates to weft-replenishing looms of the type in which two shuttles are used alternately, according to the fundamental principles illustrated and described in U. S. Letters Patent to Barrell No. 1,207,124.

In such looms as heretofore constructed there have been difficulties that have resulted in failure to thread the shuttle correctly, failures to remove the outlying ends of old filling from the new filling, with the consequent carrying of old filling back into the shed to be woven into the cloth with the new filling, premature restarting of the weaving mechanism, restarting of the weaving mechanism irrespective of failure of one kind or another in the operation of interchanging the shuttles, and in other particulars that will be understood when the complete description of the present invention has been taken into account.

My present invention is embodied in a loom that has provisions for guarding against the failures and inaccuracies hereinbefore noted, together with other improvements, all of which are hereinafter described and illustrated by the accompanying drawings.

Referring to the drawings.

Figure 1 represents an end elevation of the "change end" of a loom constructed in accordance with my present invention, the weaving mechanism being, for the most part, omitted for the sake of showing the replenishing mechanism more clearly. In this figure the clutch-controlling mechanism, by which the power is connected alternately to the weaving mechanism and to the replenishing mechanism, is in the position occupied when the loom is weaving. The lay, however, is in the position that it should occupy when the shuttles are interchanged.

Fig. 2 represents an elevation of the cam and lever that disconnect the power from the replenishing mechanism and connect it to the weaving mechanism.

Fig. 3 represents an elevation of a safety device by which the starting rockshaft is

locked to prevent restarting the weaving mechanism during the operation of interchanging shuttles.

Fig. 4 represents an elevation on a larger scale of the assemblage shown at the upper right of Fig. 1, and includes the bobbin magazine, the support for the spare shuttle, the bobbin-transferring hammer, the shuttle-carrier, and other elements that will be accounted for in due course.

Fig. 5 represents an elevation of the shuttle-carrier with a shuttle thereon, the direction of view being from front to rear.

Fig. 6 is a perspective view of the shuttle-support on which the spare shuttle is held for the reception of a full bobbin and until another change of shuttles is required. This figure includes also the device that clamps the shuttle on the support and the thread-handling devices, the latter being in the positions occupied during the shuttle-changing operation. The direction of view is from rear to front, as though the observer were standing in the foreground according to Fig. 1 and looking diagonally toward the opposite end of the loom.

Fig. 7 is a perspective view, partly in section, of the assemblage included in Fig. 6, the direction of view being from front to rear and from right to left, assuming that the observer is standing in front of the loom.

Fig. 8 represents a top plan view, partly in section, of the structure included in Figs. 6 and 7, showing the spare shuttle as having been provided with a full bobbin, and the filling end of the active shuttle extending to the fabric.

Fig. 9 represents, somewhat diagrammatically, the spare shuttle resting on its support, and its outlying end of filling drawn down into the throat of the shuttle to thread the latter prior to transferring said shuttle from said support to the shuttle-box of the lay. This figure includes broken lines that indicate two successive positions of the filling end before the latter is drawn down as shown by a continuous line.

Fig. 10 represents a perspective view of the change end of the lay, omitting the left hand portion of the screed, and omitting the movable shuttle-box front.

Fig. 11 represents an elevation of the shuttle-carrier with a full shuttle in section, showing the relation of the carrier and full shuttle during the operation of transferring

the latter from the bobbin magazine to the shuttle-box.

Fig. 12 represents a vertical section through the shuttle-box and through the shuttle-carrier, the latter having completed the transfer of the full shuttle to the shuttle-box, and being about to receive the spent shuttle from the elevator.

Fig. 13 represents a top plan view of the shuttle-carrier, and includes broken lines representing the two shuttles, the full shuttle being at the left and the spent shuttle being at the right.

Fig. 14 is a top plan view of the clutch mechanism by which the motive power is connected to the crankshaft and change shaft alternately.

The same reference characters indicate the same parts wherever they occur.

Figs. 1 and 10 illustrate the change end of the lay and the elements that constitute the shuttle-box, and include the lay 15 the shuttle binder 16, screed 17, movable shuttle-box front 18, shuttle ejector 19, and the shuttle receiver or elevator 20. The front 18 is carried by arms 21 that are mounted upon pivot member 22, and is adapted to be raised, as shown by Fig. 12, preparatory to a change of shuttles. An arm 23 that is fastened to arms 21 is connected by rod 24 to lever 25, and the latter is mounted upon a pivot member 26, and is provided with a cam roll 27 that cooperates with a cam 28. A tension spring 29 normally holds the shuttle-box front in shuttle-confining position as shown by Fig. 1, cam 28 serving to raise the shuttle-box front and hold it in its raised position until the filled shuttle has been carried to the position shown by Fig. 12. While the shuttle-carrier, hereinafter described, is in the position shown by Fig. 12 the shuttle-box front is returned to its lower position, the filled shuttle being thereby confined in the shuttle-box prior to return movement of the shuttle-carrier to the bobbin magazine.

Cam 28 and other cams hereinafter specified, are fixed upon shaft 30, the latter being usually termed "the changeshaft." Those who are acquainted with looms of this type will understand that the changeshaft remains stationary during the weaving periods, and that when a change of shuttles is required automatic feeler mechanism (not shown) disconnects the power from the weaving mechanism and connects it to the changeshaft. The changeshaft then makes one complete revolution, and when it is near the end of its cycle it actuates the aforesaid clutch mechanism in such manner as to disconnect the power from the change shaft and reconnect it to the weaving mechanism. The change shaft, in the present instance, operates with the results just stated, the cam for disconnecting the power from the

change shaft and for reconnecting it to the weaving mechanism being indicated at 31 in Fig. 2. Cam 31 actuates a lever 32, the upper arm 33 of which moves from front to rear under the influence of the cam. Arm 33 is arranged to act upon a collar 34 that is affixed to a connecting rod 35. The forward end of said rod is connected by a pivot member 36 to an arm 37. This arm is loosely mounted upon rockshaft 38, the latter being usually termed the "starting rockshaft." This rockshaft extends across the front of the loom under the breast beam and is connected at the remote end of the loom to the automatic clutch mechanism hereinbefore mentioned. For present purposes it will be sufficient to state that the rockshaft 38 is turned in a clockwise direction to connect the power to, and in a counterclockwise direction to disconnect the power from, the weaving mechanism.

It has been stated that arm 37 is mounted loosely upon the starting rockshaft. It is held thereon by a collar 39. An arm 40 is affixed to the rockshaft and is connected to arm 37 by a tension spring 41, the latter being under initial tension which is maintained by coöperative abutting portions 42 and 43 (Fig. 4), formed upon the two arms respectively. When the starting rockshaft 38 is in position to connect the power to the changeshaft arm 40 occupies the position shown by Fig. 3, and at such times the outer end of said arm is in position to be locked by a locking finger 44. This finger is affixed to a rockshaft 45 that is under the control of the spent shuttle for the purpose of preventing restarting of the weaving mechanism unless and until the spent shuttle has been accurately deposited in the position 105 that it must occupy to receive a full bobbin from the bobbin magazine. Finger 44 takes the position shown by Fig. 3 when the spare shuttle is taken by the shuttle-carrier toward the shuttle-box, and is not retracted from 110 said position until the spent shuttle has been deposited in bobbin-receiving position. In the event that the spent shuttle should be dropped, or should be incorrectly deposited upon the support under the bobbin magazine, finger 44 will remain in the position shown by Fig. 3 when the starting cam 31 actuates rod 35 to swing arm 37 from the position represented by broken lines in Fig. 4 to that shown by solid lines in the same 120 figure. Under the conditions just stated arm 40 will remain locked by finger 44 when arm 37 is moved to the rear, the only apparent result being the elongation of spring 41, the loom remaining at rest so that the attendant may remedy the cause of failure.

The locking device just described serves two desirable purposes. First, it prevents premature connection of the power to the weaving mechanism, and second it prevents 130

a sequence of operations that might result in the production of a thin place in the fabric should the attendant fail to observe the failure of the spent shuttle to take the desired or predetermined position for reloading. Whenever it is necessary to stop the loom for correcting a fault or for making an adjustment the attendant may remove the spare shuttle from its bobbin-receiving position, such removal enabling the locking finger 44 to take its locking position, and thereby guarding the attendant against whatever injury might result from starting the weaving mechanism while the fault is being remedied or the adjustment being made. When everything is in readiness for the resumption of weaving the act of replacing the spent shuttle in its bobbin-receiving position is sufficient to retract the locking finger from locking position to the position shown by Fig. 4.

In Fig. 1 the active shuttle is indicated at z , and the spare shuttle is indicated at z' . When, during the weft-replenishing cycle the front 18 has been raised, the spent shuttle is ejected from the shuttle-box by the movement of the ejector 19 toward the front of the loom. The ejector is mounted upon a pivot member 46 that is carried by the lay, the upper portion of the ejector overlying the binder 16, and being curved so as to be concentric in relation to said pivot member. The ejector extends between the binder and the screed, and its shuttle-engaging portions are bent downwardly in front of the binder as shown by Fig. 10. The ejector is actuated by a cam (not shown) on the changeshaft, through suitable well known connections that include a lever, and a connecting rod 47. The upper portion of said rod extends loosely through a stud 48 that is carried by the ejector arm 49, and that is capable of swivelling relatively to said arm. A compression spring 50 is coiled about the rod 47 and is compressed between stud 48 and a collar 51, the latter being fixed to the rod. The capacity of the spring to be compressed enables the rod 47 to rise without breaking anything should the shuttle become caught in the shuttle-box, or should the ejector be otherwise prevented from moving as intended.

Under normal conditions the spent shuttle will be pushed forwardly by the ejector and thereby transferred to the receiver or elevator 20. The latter is provided with up-standing flanges 20* that are arranged to engage the tips of the shuttle. These flanges converge and serve to register the shuttle as to endwise movement so that the shuttle will take the desired position upon the carrier and upon the support that holds it under the bobbin magazine.

When the spent shuttle has been placed upon the receiver 20 the latter is elevated to

the position shown by Fig. 12. For this purpose the receiver is mounted upon the upper end of a stem 52. The upper portion of this stem has a bearing in a bracket 53, and the lower portion has a bearing in a bracket 54. 70 Bracket 53 is carried by the lay and bracket 54 is carried by the sword-shaft 55 and oscillates therewith. Cam 56 on the changeshaft acts upon a lever 57 to raise the receiver 20. One end of said lever is mounted upon pivot member 26, and the other end has suitable sliding connection with a bracket 58 that is affixed to stem 52. As the lay swings forward and back the bracket plays forward and back idly upon lever 57. A compression spring 59 is coiled about stem 52 and is compressed between brackets 53 and 58. The up and down traverse of the receiver 20 is controlled by guides 60 on the lay.

Figs. 6, 8 and 9 afford the best showing of 85 the stationary support by which the spare shuttle is supported in bobbin-receiving position. This support comprises two separated portions 61, 61, the space between them being slightly longer than the length of the 90 bobbins, to enable the latter to be discharged from the bottom of the shuttle according to the well known practice with all shuttles that are used in conjunction with the well known Northrop bobbin magazine. A bobbin magazine of the type just mentioned is represented somewhat conventionally in Figs. 1, 4, and 9, and the bobbins therein are indicated at b' , b^2 , b^3 , etc. Without describing the magazine completely it will be sufficient 100 to state that the ends of the bobbins are supported by suitable elements that are caused to rotate step by step to move the bobbins successively into registration with the spare shuttle so that they may be transferred by 105 the usual well known hammer 62. I provide the magazine with two separated thread-disks 63 and 64. The edge of disk 63 is notched as shown by Fig. 4, each notch being adjacent the tip end of a bobbin to hold the 110 outlying weft end in the desired position as the rotatable elements of the magazine advance. The edge of disk 64 is also notched, the notches 65 thereof being preferably deep enough to guard against accidental dislodgment of the weft ends. As the full bobbins are placed in the magazine their weft ends are stretched across the disks 63, 64, and are wound around and secured to the usual weft end holder 66. The disks and holder 120 rotate with the movable bobbin-holding elements, thus maintaining the portions of thread that bridge across the space between the two disks in substantially parallel relation to the axis of the magazine. The 125 magazine is rotated by the usual well known ratchet and pawl mechanism (not shown), and as each succeeding bobbin reaches the position occupied by bobbin b' the rotative movement is arrested by the large end of the 130

bobbin, which strikes the registering stop 67, Fig. 6. As each bobbin approaches the position last specified its weft end a' is deflected downwardly by two stationary thread guides 68, 69 (see Figs. 4 and 9), the control of the weft end being thereby initiated preparatory to the threading of the shuttle.

Referring to Fig. 9 the bobbin indicated conventionally at b' is supported by the magazine and is in registration with the hammer 62 and shuttle x' . When the hammer is actuated it depresses the bobbin into the shuttle, the bobbin then occupying the position of that indicated at b . The shuttle 10 is provided with spring-jaws 70 which hold the bobbin by its large end. When the bobbin is transferred to the shuttle the weft end takes the position represented by broken line a^2 , the outer portion of the thread remaining in a notch of disk 64. At this time the weft end is held in such position that it is nearly in vertical registration with the throat x^2 of the shuttle, such registration being assisted by a movable thread guide 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 the spent shuttle is the one that retracts locking finger 44 from arm 40 of the starting rockshaft as hereinbefore explained. The deposit of the spent shuttle in bobbining-receiving position thus accomplishes two results, namely, the unlocking of the starting rockshaft, and the placing of the thread guide 71 in operative position. When the spare shuttle is subsequently taken from the support 61 the weight of finger 44 moves 70 the latter to locking position, raises thread guide 71, and places finger 73 in the position shown by Fig. 6.

The structure of the shuttle-carrier is shown best by Figs. 11, 12 and 13. The carrier comprises an oscillatory arm 74 at the upper end of which is a head 75. This head is provided with a platform for the spent shuttle, and a separate platform for the filled shuttle. The first said platform 85 comprises shuttle-supporting surfaces 76, 76 and the other comprises shuttle-supporting fingers 77, 77. The head is provided with fixed abutments 78, 78 arranged to engage the front side of the spent shuttle. A movable shuttle-retaining device 79 is carried by the head and is mounted upon a pivot pin 80. This device has shuttle-engaging portions 81, 81 arranged to engage the rear side of the spent shuttle. When the carrier is against the lay as shown by Fig. 12 the spent shuttle x is deposited between the elements 78 and 81 by the receiver 20 as the latter descends, the downward path of the shuttle being indicated in Fig. 12 by broken lines. The portions 81 are normally held in the position shown by a torsion spring 82, a portion of the device 79 being adapted to abut against a portion of the head 75 to prevent the retaining device 105 from being lifted too far by the spring. When the spare shuttle reaches the bobbining-receiving position it is arrested by the upright wall of support 61, but the shuttle-carrier continues to move to the front, the shuttle-engaging portions 81 being displaced downwardly against the stress of spring 82 by the lower edge of the shuttle. At this time the shuttle is prevented from rising by the thread guide 71, and also by a boss 83 115 that is formed upon the stationary shuttle support in position to overhang and engage the forward upper edge of the shuttle. The shuttle-carrier is arrested when it reaches the position shown by Figs. 1 and 4, the device 79 having been returned to its initial position by spring 82.

The portions 81 serve subsequently to push the spare shuttle from the support 61 as the carrier moves to the rear during the next 123 shuttle-changing cycle. The fingers 77 project to the rear in the position to sustain the spare shuttle as the latter is pushed from support 61. It will be observed that the shuttle-supporting surfaces of fingers 77 130

have a substantial inclination toward the rear of the loom, this inclination being due to the angular motion of the carrier about its pivot member 84 (Fig. 1). In order to prevent the spare shuttle from slipping from fingers 77 the carrier is provided with locking fingers 85, 85, the tips 85^x of which are hook-shaped and are arranged to extend upwardly into the bobbin cavity as shown by Fig. 11. The front wall of the shuttle drops between the tips 85^x of fingers 85 and the confronting faces of portions 81 as the shuttle is being pushed from the stationary support by the portions 81, the arc traversed by the tips of fingers 85 being slightly below the bottom of the shuttle up to the time when the portions 81 begin to push the shuttle as stated. Fingers 85 are formed upon or fastened to a tubular structure 86, and the latter is mounted upon and adapted to turn upon a pin 87 that is affixed to the head 75. A torsion spring 88 is arranged to hold the fingers normally in the position shown by Fig. 11, said fingers being capable of being depressed to release the shuttle. A pin 89, which serves as a lever for retracting fingers 85, is affixed to one of said fingers and extends downwardly in position to engage the shuttle-receiver 20. As the carrier approaches the lay with the filled shuttle the supporting fingers 77 overlap the lay as shown by Fig. 12, and the lever pin 89, striking the receiver 20, is arrested with the result that the locking fingers 85 are depressed to release the shuttle. The upper portion of the lay is provided with cavities 90, 90 to receive the fingers 85 and to permit the latter to be depressed below the bottom of the shuttle. The traverse of the carrier toward the rear is arrested by the receiver 20, the lower portion of the latter being arranged to be engaged by the head of the carrier. The momentum of the filled shuttle is sufficient to carry the latter as far as the shuttle binder 45 will permit, the front wall of the shuttle thereby advancing relatively to the tips of fingers 85, so that there will not be any possibility of catching the fingers on the shuttle when the carrier moves to the front. While the carrier remains in the position shown by Fig. 12 receiver 20 descends to deposit the spent shuttle upon the carrier, the lower portion of the receiver traversing the pin 89 incidentally to such depositing operation. When the carrier begins to move to the front the lower portion of pin 89 is in contact with receiver 20, and such forward motion is sufficient to carry the tips of fingers 85 beyond the shuttle before said tips have risen far enough to engage the shuttle. The downward motion of shuttle-box front 18 occurs while the carrier is in the position shown by Fig. 12, to retain the filled shuttle in the shuttle-box.

Referring to Fig. 1, the arm 74 of the

shuttle-carrier is moved to the rear by a tension spring 91, and is moved to the front by cam 92 on the changeshaft. A roll 93 carried by arm 74 co-operates with cam 92.

During the latter part of the forward traverse of the shuttle-carrier, and after the spent shuttle has been deposited in bobbin-receiving position, a cam plate 94, affixed to the head of the carrier, engages and depresses a roll 95 that is mounted upon a lever 96. This lever has a fulcrum pin 97 affixed thereto and mounted in a bearing 98 in a portion of the shuttle support 61. The lever is normally held in the position shown by Fig. 6 by a torsion spring 99. One end of said spring is anchored in the bearing structure 98 as shown by Fig. 8, and the other end is inserted into a hole in a collar 100. This collar is arranged upon the pin 97 and is fastened thereto by a set screw 101, the collar being set at a position that will maintain sufficient stress in the spring at all times.

One of the functions of lever 96 is to actuate threading device 72, and for this purpose a link 102 is arranged to connect the forward end of the lever with an arm 103. Said arm is affixed to the rockshaft portion 104 of the threading device 72. Spring 99 is thus utilized to move the threading device 95 downwardly from the position shown by Figs. 4 and 7, to that shown by Figs. 6 and 9, the threading movement occurring during the first stage of the shuttle-carrier's traverse toward the lay but before the carrier has taken up the filled shuttle from the support 61. The threading device 72 remains in its lower position throughout the remainder of the shuttle-changing operation, and is not raised until the cam plate 94 depresses roll 95 as the shuttle-carrier next returns to its forward position. The threading device is provided with a thread-guard 105, which is in the form of a spur and which is arranged to prevent the outlying weft end, between the thread-disks 63, 64, of the bobbin at b' from overlying the threading device when the latter rises. It sometimes happens that the weft ends become slackened so that they sag between the disks 63, 64, and when a stretch of thread is so slackened as to sag a slight agitation of the air about it is sufficient to sway it. Under such conditions the guard 105, when in the position shown by Fig. 6 prevents slackened weft ends from swinging so far to the front of the loom as to overlie the threading device. It is thus assured that the weft end of each bobbin, as the latter is carried into registration with the hammer 62, will be in position to be drawn downwardly by the threading device.

An important feature in connection with the threading of the shuttle is that the front wall of the support 61 is cut away at its

outer end to enable the thread a^3 to be drawn down to the bottom of throat x^2 . The end face of the front wall of the shuttle support is indicated at 106, and although it is nearly in line with the throat of the shuttle it is far enough in front of said line to offer no obstruction to the thread as the threading device descends. The thread guide 71 is disposed between disk 63 and stationary guide 68 (Fig. 8) and stands in the path of the weft ends that are stretched across the disks 63, 64. The thread guide 71 arrests the weft end a' as the bobbin attached thereto moves into registration with the hammer 62. Thus the guide 71 assumes control of the weft end a' before the bobbin b' is transferred to the shuttle, and moves downwardly, while engaging said weft end, into the throat of the spare shuttle as soon as the latter is deposited in bobbin-receiving position. The outer portion of thread a' is carried forward by disk 64 a considerable distance beyond the longitudinal center line of the shuttle immediately following the transfer of the bobbin to the shuttle. The rotative movement of the magazine occurs during the upward movement of the hammer. The outlying weft end of the transferred bobbin is thus carried by disk 64 to position a^2 (Fig. 8) where it is substantially in vertical registration with the throat of the shuttle, the thread remaining under the control of the guide 71, and having been depressed, throughout a portion of its length, (see a^2 , Fig. 9) into the throat of the shuttle by the bobbin. The subsequent threading motion of the threading device 72 occurs before the guide 71 is withdrawn from the throat of the shuttle, guide 71 therefore maintaining control of the thread continuously from a point of time prior to the transfer of the bobbin until the thread is depressed below it by the threading device 72.

The spare shuttle is clamped against the front wall of support 61 by a finger 107 that is affixed to lever 96, said finger being shown in clamping position by Figs. 1, 4, 7 and 8. When the shuttle-carrier starts to the rear to pick up the filled shuttle it releases lever 96 before picking up the shuttle, thus enabling spring 99 to swing the finger 107 below the path traversed by the shuttle. Finger 107 is shown in its lower position by Fig. 6.

Lever 96 is provided with a horn 108 that extends toward the shuttle-box. The function of this horn is to prevent the thread a^4 , which extends from the disk 64 to the active shuttle, from becoming entangled with thread a^2 and the other threads that are held by the thread disks. When the first pick of the filled shuttle occurs the thread a^4 is carried over the outer end of the spare shuttle, as shown by Fig. 8, but the upright portion 109 of lever 96 serves as a guard for the

thread to prevent the latter from being drawn across the shuttle so far as to interfere with the new thread a^2 . See also Fig. 7. At this time horn 108 overlies the thread a^4 and prevents the latter from being drawn over the top of the guard portion 109. In due course the thread a^4 is parted close to the selvage of the fabric by the usual temple thread cutter (not shown), and drops out of the way although it may remain attached to the weft end holder 66.

Fig. 1 includes mechanism for actuating the hammer 62 during the first forward beat of the lay following a change of shuttles. An arm 110, which is suitably connected to the hammer, extends downwardly, and at its lower end a dagger 111 is connected thereto by a pivot pin 112. This dagger extends toward the rear and its rear end is pointed to conform to a fish-tail member 113 that is carried by but disposed under the lay. When the dagger is in the position shown by Fig. 1 its rear end is below the path traversed by the member 113, the latter, under such conditions, being free to play forward and back over the dagger without engaging the latter. The rear portion of the dagger rests upon the upper end of a rod 114, said rod extending through a guide 115, and having telescoping connection with a link 116. The lower end of this link is connected to the forward end of a lever 117 by a pivot pin 118. The rear end of the latter is mounted upon fulcrum pin 26, and a boss 119 formed upon the lower edge of the lever bears upon a cam 120 that is carried by the changeshaft. A compression spring 121 is coiled about rod 114 and is compressed between a portion of link 116 and a collar 122 on the rod, the spring affording a yielding connection between the link and the rod. When, during the cycle of the changeshaft, lever 117 is raised by the cam 120, the dagger is raised into the path of member 113. A pin or boss 123 carried by the dagger engages a weighted latch 124 in such manner that when the dagger is raised far enough to carry the boss above the upper end of the latch the latter tilts in a clockwise direction about its pivot pin 125 until its tilting motion is arrested by a stop 126. The upper end of the latch is thus arrested under the boss 123, and when the rod 114 descends the dagger is retained in its upper position by the latch. Then, during the next beat of the lay, member 113 moves the dagger forward and imparts bobbin-transferring movement to hammer 62 and incidentally thereto boss 123 is carried forward beyond latch 124 so that the dagger may drop to its initial position when released by member 113.

Fig. 1 also includes the crankshaft 127 and one of the connecting links 128 by which the crankshaft is connected with the lay to reciprocate the latter. The lay and its op-

erating connections just described are a sufficient representation of the weaving mechanism for the present purposes, and it may be understood that the motive power for operating the loom is connected alternately to the crankshaft and to the changeshaft in accordance with the usual practice in the well known Stafford loom.

Fig. 14 shows suitable clutch-operating mechanism arranged to disconnect the motive power from the change shaft 30 and connect it to the crankshaft 127 when the change shaft has completed a cycle. A continuously driven sleeve 129 carries a disk 130 that serves as the driving member of the clutch for the change shaft. The driven member 131 of the clutch carries a dog 132 on a pivot 133. One end of this dog is arranged to form driving connection between 130 and 131, and the other end is arranged to engage a knock-off member 134. The latter becomes effective as the change shaft is about to complete its cycle, and continues to hold the dog clear of 130 throughout the weaving period. The usual feeler-mechanism controls the movement of 134 that releases the dog to connect the change shaft to its driver.

When the rockshaft 38 is turned by the change shaft it reconnects the motive power to the crankshaft 127 by operating the following mechanism. A starting handle 135, affixed to rockshaft 38, is connected by link 136 to one end of lever 137. The other end of the latter is connected by link 138 to shipper lever 139. The fulcrum pins of said levers are at 140 and 141 respectively. Lever 139 is arranged to move a continuously rotating clutch member 142 into driving contact with a driven clutch member 143. Members 142 and 143 are mounted on the crankshaft 127, and are loose and tight respectively.

I claim—

1. A loom comprising a support for holding a spare shuttle, a controller for connecting the motive power to the weaving mechanism, means arranged to lock said controller against moving to connect the motive power as aforesaid, said means including a member that is movable to release said controller, said member being arranged to move automatically from a position of release to locking position, and movable means arranged to restrain said member in said position of release, said restraining means being arranged to be held in restraining position by a shuttle on said support.

2. A weft-replenishing loom comprising a support for a spare shuttle, weaving mechanism and shuttle-changing mechanism arranged to operate alternately, said shuttle-changing mechanism being arranged to interchange a shuttle on said support and a shuttle in the change shuttle-box of the lay,

a controller for shipping the motive power from said shuttle-changing mechanism to the weaving mechanism, means arranged to be operated by said shuttle-changing mechanism to move said controller to ship the motive power as aforesaid, and means arranged to lock said controller automatically against moving as aforesaid when no shuttle is on said support, said locking means being arranged to be rendered non-locking by a shuttle as the latter is placed on said support by said shuttle-changing mechanism.

3. A weft-replenishing loom comprising a support for a spare shuttle, weaving mechanism and shuttle-changing mechanism arranged to operate alternately, said shuttle-changing mechanism being arranged to interchange a shuttle on said support and a shuttle in the change shuttle-box of the lay, a starting rockshaft for connecting the motive power to said weaving mechanism, means arranged to be operated by said shuttle-changing mechanism to move said rockshaft to connect the motive power as aforesaid, and means for locking said rockshaft against moving as aforesaid, said locking means being arranged to be held in non-locking position by a shuttle on said support and being adapted to move automatically to locking position when the spare shuttle is removed from said support.

4. A weft-replenishing loom comprising a support for a spare shuttle, a change-shaft, a starting rockshaft for shipping the motive power from said change-shaft to the weaving mechanism, means operative by said change-shaft to turn said rockshaft to ship the motive power as aforesaid, means arranged to lock said rockshaft automatically against turning as aforesaid, said locking means being arranged to be held in non-locking position by a shuttle on said support, and means arranged to transfer a shuttle from said support to the change shuttle-box of the lay.

5. A weft-replenishing loom comprising a change-shaft and weaving mechanism arranged to operate alternately, a support for a spare shuttle, shuttle-changing mechanism arranged to be operated by said change-shaft to interchange a shuttle on said support and a spent shuttle in the change shuttle-box of the lay, a controller for shipping the motive power from said change-shaft to the weaving mechanism, means arranged to be operated by said change-shaft to move said controller, means arranged to lock said controller against moving to ship the motive power as aforesaid, said locking means including a member arranged to be depressed by a shuttle on said support and thereby retracted from locking position, and means arranged to overhang and engage the shuttle, as the latter is being placed on said support by said shuttle-changing mechanism,

to insure the depressing action of the shuttle on said member as aforesaid.

6. A weft-replenishing loom comprising a change shuttle-box, a support for a spare shuttle, means arranged to put a full bobbin into the shuttle on said support, means arranged to interchange the shuttle on said support and a spent shuttle in said shuttle-box, and movable means arranged to be moved by the spent shuttle, as the latter is being deposited on said support by said shuttle-changing mechanism, to guide the weft-end to the throat of the spent shuttle, said guiding means including a thread-guiding member arranged to be moved to contiguous relation with the shuttle by the action of the latter.

7. A weft-replenishing loom comprising means arranged to put a full bobbin into a spent shuttle, means arranged to transfer a spent shuttle from the lay to bobbin-receiving position relatively to the first said means, a thread-guide arranged to move to and from a shuttle in said position, and means arranged to be engaged and moved by a shuttle, as the latter moves to said position, to move said thread-guide to contiguous relation with the shuttle.

8. A weft-replenishing loom comprising a shuttle-support, mechanism arranged to transfer a spent shuttle from the change shuttle-box to said shuttle-support and back to said shuttle-box, means arranged to hold a full bobbin over the shuttle on said support, means arranged to hold the weft-end of such bobbin, means arranged to transfer such bobbin into the shuttle on said support, and means arranged to depress said weft-end, externally of the shuttle, below the level of the bobbin in the shuttle while the latter is on said support, to place the weft-end in the throat of the shuttle.

9. A weft-replenishing loom comprising a shuttle-support, shuttle-transferring mechanism including a shuttle-carrier arranged to carry a spent shuttle from the change shuttle-box to said support and back to said shuttle-box, means arranged to hold a full bobbin over the shuttle on said support, means arranged to hold the weft-end of said bobbin, means arranged to be moved by the spent shuttle, as the latter is deposited on said support, to guide said weft-end, said guiding means including a thread-engaging member arranged to be moved to contiguous relation with the top of the shuttle by the action of the latter, means arranged to transfer the full bobbin from said holding means into the shuttle on said support, and means controlled by said shuttle-carrier to depress said weft-end, externally of the shuttle, below the level of the bobbin in latter, while said shuttle is on said support, to place the weft end in the throat of the shuttle.

10. The combination with a loom having a change shuttle-box, of a shuttle having an open throat, a shuttle-support, mechanism arranged to transfer the shuttle from said shuttle-box to said shuttle-support and back to said shuttle-box, means arranged to put a full bobbin into the shuttle on said support, means arranged to hold the weft-end of such bobbin, and means arranged to move said weft-end to the bottom of said throat throughout the length of the latter while the shuttle is on said support.

11. The combination with a loom having a change shuttle-box, of two shuttles each having an open throat, a shuttle-support, means arranged to interchange said shuttles on said support and in said shuttle-box respectively, a bobbin-magazine, means arranged to transfer a full bobbin from said magazine into the shuttle on said support, means arranged to hold the weft-ends of the bobbins in said magazine, means arranged to engage the throat portion of the shuttle on said support to guide the weft-end into the throat, and threading means arranged to engage the weft-end between the shuttle and said end-holding means, said threading means being arranged to move the weft-end to the bottom of the throat of the shuttle.

12. The combination with a loom having a change shuttle-box, a shuttle-support, and mechanism arranged to interchange a spent shuttle and a spare shuttle in said shuttle-box and on said shuttle-support respectively, of means arranged to put full bobbins into the shuttles alternately as the latter are on said support, a holder for holding the weft-ends of the full bobbins, shuttle-engaging means arranged to guide the weft thread to the top of the shuttle as a full bobbin is put into the latter, and a shuttle-threading means arranged to depress the outlying weft thread, tangentially to the shuttle, below the level of the bobbin in the shuttle while the latter is on said support.

13. The combination with a loom having a change shuttle-box, a shuttle-support, and mechanism arranged to interchange a spent shuttle and a spare shuttle in said shuttle-box and on said support respectively, a magazine for full bobbins, means arranged to transfer a full bobbin from said magazine to a shuttle on said support, and means arranged to depress the outlying thread of said bobbin, externally of and tangentially to the shuttle, below the level of the bobbin while the shuttle is on said support, to lay the thread on the bottom of the throat of the shuttle.

14. A weft-replenishing loom comprising weaving mechanism and shuttle-changing mechanism arranged to operate alternately, a support for a spare shuttle, said shuttle-changing mechanism including a shuttle-carrier arranged to transfer a spare shuttle

- from said support to the change shuttle-box, and movable means carried by said carrier and arranged to hold the spare shuttle on the carrier, said holding means having a part 5 arranged to engage a part carried by said shuttle-box in consequence of moving toward the latter, to move said holding means relatively to the carrier to release the shuttle thereon.
- 10 15. A weft-replenishing loom comprising weaving mechanism and shuttle-changing mechanism arranged to operate alternately, a support for a spare shuttle, said shuttle-changing mechanism including a shuttle- 75 carrier arranged to transfer a spare shuttle from said support to the change shuttle-box, a locking device movably mounted on said carrier and having a shuttle-engaging portion arranged to project upwardly from the 15 plane of the shuttle-supporting surface of the carrier to hold the shuttle against displacement, said device having a part below said plane for retracting said shuttle-engaging portion to release the shuttle, and a 20 member carried by said shuttle-box and arranged to be engaged by said part as the carrier moves toward said shuttle-box, to cause shuttle-releasing movement of said device as aforesaid.
- 25 30 16. A weft-replenishing loom comprising weaving mechanism and shuttle-changing mechanism arranged to operate alternately, a support for a spare shuttle, said shuttle-changing mechanism including a shuttle- 95 carrier arranged to transfer a spare shuttle from said support to the change shuttle-box, a device pivotally mounted on said carrier and arranged to engage the spare shuttle thereon to hold the shuttle against displacement, a spring arranged to hold said device in locking position, said device having a part which, when arrested as the carrier is moving toward said shuttle-box, is arranged to retract said device from shuttle-holding position, and a member carried by said shuttle- 100 box and arranged to arrest said part to retract said device as aforesaid.
- 35 40 17. A weft-replenishing loom comprising a support for a spare shuttle, weaving mechanism and shuttle-changing mechanism arranged to operate alternately, said shuttle-changing mechanism including means arranged to eject the spent shuttle from the change shuttle-box and a lifter arranged to raise and lower the ejected shuttle, said shuttle-changing mechanism including a shuttle-carrier arranged to carry the spare shuttle from said support to said shuttle-box and to carry the ejected shuttle from 105 said support, and means carried by said carrier to hold the spare shuttle against displacement thereon, said lifter and said holding means being arranged to coact with each other to retract the latter from 110 45 shuttle-holding position.
- 45 50 18. A weft-replenishing loom comprising a support for a spare shuttle, weaving mechanism and shuttle-changing mechanism arranged to operate alternately, said shuttle-changing mechanism being arranged to 70 interchange a spent shuttle and a spare shuttle in the change shuttle-box and on said support respectively, a bobbin-magazine arranged in front of said shuttle-box, said support being arranged under said magazine, a holder arranged to hold the weft-ends of the bobbins, means arranged to transfer a bobbin from said magazine to the shuttle on said support, a thread-guard movable to and from a position between said 80 shuttle-box and the shuttle on said support to hold the weft-thread connecting the active shuttle and said holder away from the new weft thread of the spare shuttle, and means arranged to move said thread-guard from 85 said position during the shuttle-changing period to clear the path of the shuttles.
- 55 60 19. A loom comprising a support for a spare shuttle, weaving mechanism and shuttle-changing mechanism arranged to operate 90 alternately, said shuttle-changing mechanism being arranged to interchange a spare shuttle on said support and a spent shuttle in the change shuttle box of the weaving mechanism, a shipper for applying the motive power to said weaving mechanism, and means controlled by said shuttles alternately to lock said shipper when both shuttles are off said support and to unlock the shipper when one of the shuttles is on said support. 95
- 65 70 20. A loom comprising a support for a spare shuttle, weaving mechanism and shuttle-changing mechanism arranged to operate alternately, said shuttle-changing mechanism including means arranged to transfer a spare shuttle from said support to the change shuttle box of the weaving mechanism, a shipper for applying the motive power to said weaving mechanism, and means arranged to lock said shipper automatically when the spare shuttle is removed from said support, said means being arranged to be moved to unlocking position by a shuttle resting on said support. 100
- 75 80 21. A loom comprising means arranged 115 to put a full bobbin into a square shuttle, weaving mechanism and shuttle-changing mechanism arranged to operate alternately, said shuttle-changing mechanism being arranged to interchange the spare shuttle and a spent shuttle in the change shuttle-box of the weaving mechanism, a shipper for connecting the motive power to drive the weaving mechanism, and means arranged to lock said shipper automatically when no shuttle 120 is in bobbin-receiving position relatively to the first said means, said locking means being movable by a shuttle to unlock the shipper as the shuttle arrives at said position.
- 85 90 22. A weft-replenishing loom comprising 125 130

- weaving mechanism, disconnectible power-driven means for operating the weaving mechanism, automatic mechanism arranged to put a full bobbin into a spare shuttle,
5 automatic mechanism arranged to interchange the spent shuttle and the filled spare shuttle, and means arranged to lock said power-driven means in disconnected position, said locking means being arranged to
10 be controlled by the spare shuttle so as to permit the power-driven means to be reconnected only when the spare shuttle is in a predetermined bobbin-receiving position relatively to the shuttle-loading mechanism:
15 23. A loom comprising weaving mechanism and shuttle-changing mechanism ar-

ranged to operate alternately, power-driven means arranged to drive said mechanisms alternately and to be disconnected from each in turn, automatic mechanism arranged 20 to put a full bobbin into the spare shuttle, means arranged normally to connect said power driven means to the weaving mechanism after each interchange of shuttles, and means arranged normally to prevent operation of said connecting means but to be displaced by a shuttle in a predetermined bobbin-receiving position so as to permit said connecting means to function.

In testimony whereof I have affixed my 30
signature.

WILLIAM TOWLER.
